CLAIM

I claim the ornamental design for a bandsaw frame, as shown and described.

DESCRIPTION

FIG. 1 is a perspective view of a bandsaw frame in accordance with our new design, the broken lines of the bandsaw frame are for illustrative purposes only and form no part of the claimed design;

FIG. 2 is a right side elevation view of the bandsaw frame of FIG. 1;

FIG. 3 is a left side elevation view of the bandsaw frame of FIG. 1;

FIG. 4 is a rear elevation view of the bandsaw frame of FIG. 1;

FIG. 5 is a front elevation view of the bandsaw frame of FIG. 1;

FIG. 6 is a top view of the bandsaw frame of FIG. 1; and, FIG. 7 is a bottom view of the bandsaw frame of FIG. 1.
